UNITED STATES PATENT OFFICE.

GIBBS HUNTRY, OF CARO, MICHIGAN.

BILL-FILE.

1,226,522.

Specification of Letters Patent. Patented May 15, 1917.

Application filed July 10, 1916. Serial No. 108,452.

To all whom it may concern:

Be it known that I, GIBBS HUNTRY, a citizen of the United States, residing at Caro, in the county of Tuscola and State of Michigan, have invented new and useful Improvements in Bill-Files, of which the following is a specification.

This invention comprehends the provision of a bill file or the like embodying a fixed member and a relatively movable coöperating member to automatically lock the bills on the file, and yet permit the same to be easily and quickly removed when desired.

The invention further embodies the desired features of simplicity in construction, cheapness to manufacture, it being durable and easily manipulated as described.

The nature and advantages of the invention will be better understood when the following detail description is taken in connection with the accompanying drawing, the invention residing in the construction, combination and arrangement of parts as claimed.

In the drawing forming part of this specification like numerals of reference indicate similar parts in the several views and wherein:

Figure 1 is a front elevation of the preferred form of the invention.

Fig. 2 is a side elevation showing the adjusted position of the movable member by dotted lines.

Fig. 3 is a front elevation of a modified form.

Fig. 4 is a sectional view taken on line 4-4 of Fig. 3.

Referring to the drawing in detail and particularly to Figs. 1 and 2, an elongated plate 10 has secured thereto the coöperating members of a file, and in this instance the plate 10 is adapted to be secured to a desk or other suitable support by means of the fastening elements 11. Secured to the plate 10 adjacent its lower edge as at 12 is one end of the fixed member 13 of the file, which member projects forwardly from the plate 10 and is of substantially U-shaped formation in cross section at one end thereof. Secured to the plate 10 at a point adjacent its upper end is one terminal of the relatively movable member 14, which is curved outwardly and downwardly as shown, with the lower extremity of the curved portion extending upwardly as at 15 and terminating to provide a horizontally disposed portion

16 which is adapted to be received within the U-shaped extremity of the fixed member 13 under normal conditions. In this position the horizontally disposed portion 16 of the relatively movable member forms a continuation of the fixed member 13 and provides a satisfactory support or file for bills and the like. It is of course to be understood that the length of this support can be varied without departing from the spirit of the invention. The lower extremity of the member 14 and the extension 15 defines a manipulating portion adapted to be engaged by the finger for the purpose of retracting the horizontal portion 16 out of engagement with the fixed member 13 as illustrated by dotted lines in Fig. 2, when it is desired to place a bill upon the file or remove one therefrom. In either instance the bills upon the file can be moved forwardly or rearwardly at one or the other side of the joint between the respective members, prior to the separation of the member 14 from the fixed member 13. The component parts of the device may be constructed from any suitable material, preferably resilient wire, under which circumstances the relatively movable member 14 automatically returns to its normal position when released by the user of the device.

The modified form of the invention is illustrated in Figs. 3 and 4 wherein a base 17 is adapted to be secured to a suitable support, and from which base rises a standard 18. Encircling the standard for rotation thereabout is a sleeve 19, from which a plurality of fixed members 20 project at diametrically opposite points. The members 20 are similar in construction to the members 13 hereinabove described in connection with the preferred form of the invention, each being substantially U-shaped in cross section adjacent its free extremity for the reception of the adjacent end of the movable member 21. The member 21 preferably consists of an arcuate shaped piece of wire loosely fitted about the standard 18 at the upper end thereof, and extended outwardly and downwardly at the opposite sides of the sleeve 19. The lower extremities of the member 21 are curved upwardly as at 22 and then extended horizontally as at 23 in the direction of the sleeve 19 and fitted within the open ends of the fixed members 20. The horizontal extension 23 cooperates with the fixed member 20 to provide a satisfactory support for the bills or

the like, while the lower extremities of the movable member 21 define manipulating portions adapted to be engaged by the finger in separating the horizontal extension 23 of the movable member from the fixed member 20, which of course is done only when it is desired to remove a bill from the file or place one thereon. This form of the invention is manipulated in the same manner as the preferred form, except that the bill file proper is mounted for rotation and susceptible of being moved into a convenient position for use.

While I have shown and described what I consider the best forms of the invention, I desire to have it understood that I do not limit myself to this precise construction and arrangement and that such changes may be resorted to when desired as fall within the scope of what is claimed.

What is claimed is:—

1. A device of the class described com-

prising a support, a fixed member projecting therefrom, a relatively movable resilient member mounted upon the support and forming a continuation of the fixed member, and said movable member being provided with a depending finger engaging manipulating loop.

2. A device of the class described comprising a base, a standard rising therefrom, a sleeve rotatably mounted on said standard, a fixed member projecting horizontally from said sleeve, a relatively movable member constructed from resilient material carried by the sleeve and having its free end removably engaging said fixed member and forming a continuation thereof, and said movable member being formed to provide a finger engaging manipulating portion for the purpose described.

In testimony whereof I affix my signature.

GIBBS HUNTRY.
